(57) **CLAIM**

The ornamental design for a watercraft anchor protection device, as shown and described.

DESCRIPTION

FIG. 1 is a bottom perspective view of a watercraft anchor protection device in a folded position.

FIG. 2 is a bottom view of the watercraft anchor protection device in a folded position shown in FIG. 1.

FIG. 3 is a top view of the watercraft anchor protection device in a folded position shown in FIG. 1.

FIG. 4 is a front view of the watercraft anchor protection device in a folded position shown in FIG. 1.

FIG. 5 is a rear view of the watercraft anchor protection device in a folded position shown in FIG. 1.

FIG. 6 is a left-side view of the watercraft anchor protection device in a folded position shown in FIG. 1.

FIG. 7 is a right-side view of the watercraft anchor protection device in a folded position shown in FIG. 1.

FIG. 8 is a top perspective view of the watercraft anchor protection device in a folded position shown in FIG. 1 attached to an anchor and straps; and,

FIG. 9 is a top perspective view of the watercraft anchor protection device in an unfolded position.

(Continued)

The broken lines in FIG. 8 depict environmental structure which forms no part of the claimed design.
